UNITED STATES PATENT OFFICE.

WILLIAM M. JONES, OF CHECOTAH, OKLAHOMA.

HAIR-SPRING-COLLET REMOVER.

1,303,560.

Specification of Letters Patent. Patented May 13, 1919.

Application filed June 27, 1916, Serial No. 106,201. Renewed March 21, 1919. Serial No. 284,174.

To all whom it may concern:

Be it known that I, WILLIAM M. JONES, a citizen of the United States, and a resident of Checotah, in the county of McIntosh and 5 State of Oklahoma, have invented a certain new and useful Hair-Spring-Collet Remover, of which the following is a specification, reference being had to the accompanying drawings.

10 This invention relates to an improvement in watch-makers' instruments and comprises a device for expeditiously removing a hair spring collet from its staff.

15 The object of the invention is to provide a simply constructed, positively operating instrument by means of which a hair spring collet can be removed from its staff without in any way damaging the hair spring.

20 A further object is to provide a hair spring collet remover of a simple and inexpensive nature and of a compact and durable construction and which is so constructed as to facilitate the removal of the hair spring collet with ease, accuracy and despatch.

25 With these and other objects in view, the present invention consists in the combination and arrangement of parts as will be herein-after more fully described and finally pointed out in the appended claims, it being further understood that changes in the specific 30 structure shown and described may be made within the scope of the claims without departing from the spirit of the invention.

In the accompanying drawings forming 35 a part of this specification, and in which like numerals of reference indicate similar parts in the several views:—

Figure 1 shows a top view of a hair spring collet remover embodying my invention dis- 40 closing a balance wheel in position.

Fig. 2 is a sectional view through Fig. 1.

Fig. 3 is a sectional view disclosing the spring fingers as raised.

Fig. 4 is a transverse sectional view.

45 Fig. 5 is a perspective view of the plunger.

In my present invention I provide a watch maker's instrument used in the construction and repair of watches and providing a means 50 for holding the balance wheel of a watch in secure position in the operation of securing a hair spring collet as well as providing a means for expeditiously removing the hair spring collet from its staff.

In carrying out the aim of my invention I 55 employ a base plate formed with a middle lengthwise extending aperture 1. This aperture as shown in the drawings is located near one end of the base plate A and communicating with this aperture which extends 60 entirely through the base plate is the groove 3. For the sake of convenience, this base plate A is mounted upon the legs 10.

Secured approximately at mid-length of the aperture and upon opposite sides are two 65 similar hook arms 2, 2, these hook arms having their ends directed toward the grooved end of the plate. These hook arms 2, are ar- 70 ranged to receive the two arms *a* carrying the sector-shaped balance wheel portions *w* as is usual in the art. Passing through the union of the arms *a* is a staff *u* to which is secured a barrel B and a disk *z*, these instru- 75 mentalities being arranged against what forms the under face of the arms *a*, while se- cured to the staff *u* and upon the upper face of the arms is a hair spring collet C to which is secured the hair spring S. The operation of removing a hair spring collet from its staff requires careful manipulation in order 80 that no damage may be done the very deli- cate hair spring or staff.

In my present invention, I provide a re- 85 mover by means of which the collet may be forced off of the staff without any injury being done to the spring, no working effects coming into contact with the spring during the operation of removing the collet.

Reciprocating and sliding within the groove 3 is a plunger 4 this plunger having 90 at what forms its inner end a slit 5 as shown in Fig. 5, this slit end being transversely re- duced to a width slightly less than the width of the groove 3 and also being vertically at- tenuated as shown in Fig. 5, to provide two 95 spring fingers 11. As shown, each of these spring fingers 11, ends in a rectangular up- standing chisel-edged ear 6. Each ear 6 has its inner face 7 cut away to provide a V- shaped seat communicating with the slit 5. 100 It should be remembered that this seat is of a width less than the diameter of the staff *u*, so that when said ears are brought into en- gagement with said staff they are spread.

The plunger 4 is provided with a collar 8 105 ending in an operating head 9. The plunger 4 is of such a length that the collar 8 serves as a stop, limiting the incursion of

the fingers 11 so that the inward movement of the plunger will stop at a point just before the outer faces f of the ears 6 contact with the balance wheel arms a as shown in Figs. 2 and 3.

In order to hold the plunger 4 within the groove 3 I provide a keeper spring 16 having a lengthwise curvature insuring both of its ends being in spring pressed contact with the plunger 4. As shown in Fig. 1, this spring 16 has an extension 17, this extension 17 being of such a length that it engages over the outer faces of the spring fingers 11.

By means of this keeper spring the plunger is securely but slidably held within its groove while the fingers 11 are normally pressed downward.

Extending transversely through the base A and at a point communicating with the aperture 1 is a cam shaft 12 having the cam 13, the shaft 12 being operated by means of the handle 15. As shown in Fig. 2 the cam 13 has a face 14 which in one of its positions ends in a plane coinciding with the bottom of the groove 3 so that the face 14 forms in effect a continuation of the bottom of the groove 3.

This cam 13 is at a point below the spring fingers when said fingers are advanced.

The projection of the plunger 4 is limited by means of the end e of the spring 17 which comes into contact with the upstanding ears 6.

In order to provide a means for holding the cam face 14 in alinement with the bottom of the groove, I provide a detent comprising a U-shaped spring wire member 19 from which extends an upwardly extending resilient locking stem 20. This locking stem 20 at a suitable point has a seat 24 as shown in Fig. 4 into which the handle 15 springs. In bringing the handle 15 into engagement with the resilient locking stem 20 this stem 20 is forced inward, a seat 23 being provided in the base A as shown in Fig. 1. By means of this seat 24 the cam 13 may be securely held in proper alinement. The stem 20 is provided with an upward stop end 21 limiting the upward movement of the handle 15. The downward movement of the handle is checked by the spring 17 which limits the upward movement of the spring fingers. While in use, as shown in Figs. 1, 2, 3, and 4, the base upon which the instrument rests would serve as a stop limiting the downward movement of the handle 15. If the handle 15 is carried beyond the lower end of the legs 10 the keeper spring 17 acts as a stop.

The shaft 12 is held in position by means of a washer 22 which is interposed between the flanged end 25 of the shaft 12 and the edge of the base plate A, as shown in Fig. 4. As shown in Fig. 4 the washer 22 is normally held against the outer face of the base A by means of the handle 15, which is in

normal spring-pressed engagement with the resilient locking stem 20, thus preventing any casual lateral movement of the shaft 12.

When it is desired to use the instrument in removing the hair spring collet the balance wheel with the attached collet is placed upon the upper face of the base plate A, as shown in Fig. 1. The width of the aperture 1 is such as to snugly accommodate the disk w ; so that after being inserted the staff u will be in alinement with the slit 5 within the plunger. On advancing the plunger 4, the faces f of the ears 6 come into engagement with the arms a and force the arms outward under the hook arms 2. These hook arms 80 then stop the outward movement of the arms. At the same time, the chisel-edged ends of the ears will have been forced under the collet and against the upper face of the arms a . The ears 6 are then raised in tilting the handle 15 downward which actuates the cam 13 and raises the spring fingers 11 in lifting the collet off entirely from the staff u , as shown in Fig. 3.

Fig. 2 shows the ears in position just previous to raising the fingers.

As explained, the fingers are spread when they engage the staff u so that these fingers tightly clasp the staff u while being raised.

In referring to Figs. 2 and 3, it will be noticed that the end e of the spring extension 17 ends at a point outside the outer periphery of the wheel sectors w , so that in withdrawing the plunger 4 the inner faces of the ears 6 engage the wheel to remove the stem from below the hook arms 2.

A collet remover constructed according to my invention is inexpensive and positive in operation and a collet may be expeditiously removed from its staff without in any way injuring the balance wheel parts of the hair spring.

Having thus described my said invention, what I claim as new and desire to secure by U. S. Letters Patent is:—

1. The combination with a base, of a plunger slidably held to said base, ending in two spring fingers terminating in chisel-edged ears, means to hold said plunger to said base, and means for raising said spring fingers.

2. The combination with a base having an aperture with a groove communicating with said aperture, of a plunger within said groove ending in two spring fingers held within said aperture, each spring finger terminating in a chisel-edged ear, means to hold said plunger to said groove, and means for raising said spring fingers.

3. The combination with a base having an aperture with a groove communicating with said aperture, of a plunger within said groove ending in two spring fingers held within said aperture, each spring finger terminating in a chisel-edged ear, means to

hold said plunger to said groove, means for raising said spring fingers, and means for limiting the withdrawal of said plunger.

4. The combination with a base having an aperture with a groove communicating with said aperture, of a plunger within said groove ending in two spring fingers held within said aperture, each spring finger terminating in a chisel-edged ear, means to hold said plunger to said groove, means for raising said spring fingers, and means for limiting the projection of said plunger.

5. The combination with a base having an aperture with a groove communicating with said aperture, of a plunger within said groove ending in two spring fingers held within said aperture, each spring finger terminating in a chisel-edged ear, means to hold said plunger to said groove, means for raising said spring fingers, means for limiting the withdrawal of said plunger, and means for limiting the projection of said plunger.

6. The combination with a base having an aperture with a groove communicating with said aperture, of a plunger within said groove ending in two spring fingers each spring finger terminating in a chisel-edged ear, a cam for raising said fingers, and means for determining the position of said

30 cam.
7. The combination with a base having an aperture with a groove communicating with said aperture, of a plunger within said groove ending in two spring fingers each spring finger terminating in a chisel-edged ear, a cam for raising said fingers, means for determining the position of said cam, means for limiting the withdrawal of said plunger,

and means for limiting the projection of said plunger.

8. An instrument for removing a hair spring collet from its staff carried by a balance wheel, comprising a base having an aperture to receive said staff, means carried by said base for holding said balance wheel, a plunger slidably held to said base ending in two spring fingers each terminating in a chisel-edged ear arranged to be brought below said collet, and means for raising said spring fingers.

9. The combination with a base, having a middle lengthwise extending aperture with a communicating groove, a plunger bar sliding within said groove terminating in two attenuated transversely reduced spring fingers each ending in an upstanding rectangular chisel-edged ear, said fingers extending partly across said aperture, the inner faces of said ear being cut away to provide a V-shaped seat communicating with the slit between said fingers, an operating head at the end of said plunger limiting the projection of said plunger, a cam shaft having a cam located below said spring fingers, and a spring to force said fingers into engagement with said cam and hold said plunger within said groove, said cam on being rocked raising said fingers, as, and for the purpose set forth.

In testimony whereof I affix my signature, 70
in the presence of two witnesses.

WILLIAM M. JONES.
